G. H. EMERY

REFRIGERATING APPARATUS

Filed Aug. 5, 1922

Inventor:

Gustav H. Emery

By

Attorney

UNITED STATES PATENT OFFICE.

GUSTAV H. EMERY, OF WASHINGTON, DISTRICT OF COLUMBIA, ASSIGNOR TO PABLO BROQUIER, OF MADRID, SPAIN.

REFRIGERATING APPARATUS.

Application filed August 5, 1922. Serial No. 579,930.

To all whom it may concern:

Be it known that I, GUSTAV H. EMERY, a citizen of the United States of America, residing at Washington, District of Columbia, have invented certain new and useful Improvements in Refrigerating Apparatus, of which the following is a specification.

My invention relates specifically to apparatus for cooling air, water or any other medium for refrigerating purposes. This invention utilizes the theory that the evaporation of water causes a reduction in temperature of surrounding bodies which is carried out by allowing the medium to be cooled to flow as close as possible to the place where the evaporation is carried on. The object of this invention is to increase the evaporating surface at the same time providing means for quickly moving the air which is saturated with water vapor, from the surface of the apparatus. A further object is to provide additional means for cooling the refrigerating medium.

I attain these objects by the apparatus and showing illustrated in the accompanying drawing, which illustrates a diagrammatic showing of the system.

Referring now to the drawing, in which similar numerals refer to similar parts throughout, numeral 1 denotes a cylindrical tube suitably mounted on a shaft 2 and having an inlet end 11 and an outlet end 12. The shaft is mounted in suitable bearings 3 and has mounted thereon a wheel 4 between the bearing and outlet of the tube. When the wheel is rotated by any suitable means, not shown, the shaft is rotated and thereby the tube. Suitably located but preferably above the tube is mounted a water pipe 6 having a plurality of small holes 7 therein so that the outside of the tube may be continuously moistened as fast as the water is allowed to evaporate depending upon the speed of the tube. At the inlet end of the tube any connecting means, not shown, may be utilized for carrying the medium to be cooled to the tube.

The tube 1 is provided on the inside surface with a spiral rib 10 which increases the cooling surface at the same time aiding the cooling medium, such as air, through the tube. On the outside of the tube are a plurality of annular ribs 8 for the purpose of increasing the evaporating surface. Suitably spaced along the outside of the tube and between the annular ribs are a plurality of wings 9 for the purpose of more quickly removing the saturated air from the evaporating surface in any predetermined direction.

The operation of the device is as follows: During the rapid rotation of the tube 1 the water, which is continuously supplied from the pipe 6, evaporates and lowers the temperature of the tube. The refrigerating medium passing through said tube is thereby cooled being aided by the ribbed construction of the rotating tube.

I claim as my invention:

1. Refrigerating apparatus, comprising a cylindrical tube adapted for rotation; means for forcing air through the tube; means for supplying a liquid on the surface of said tube; and wings on the outside of the tube.

2. Refrigerating apparatus, comprising a shaft; a cylindrical tube adapted for rotation on said shaft; means for forcing air through the tube; means for supplying water on the surface of said tube; and a plurality of wings on the outside of the tube.

3. Refrigerating apparatus, comprising a shaft; a cylindrical tube adapted for rotation on said shaft; means for forcing air through the tube; annular ribs on the surface of said tube; a pipe for supplying water to said tube; and a plurality of wings on the surface of the tube.

In testimony whereof I affix my signature.

GUSTAV H. EMERY.

Certificate of Correction.

It is hereby certified that in Letters Patent No. 1,468,999, granted September 25, 1923, upon the application of Gustav H. Emery, of Washington, District of Columbia, for an improvement in "Refrigerating Apparatus," an error appears requiring correction as follows: In the drawing the figure should appear as shown below instead of as shown in the drawing:

and that the said Letters Patent should be read with this correction therein that the same may conform to the record of the case in the Patent Office.

Signed and sealed this 30th day of October, A. D., 1923.

[SEAL.]

KARL FENNING,
Acting Commissioner of Patents.
